UNITED STATES PATENT OFFICE.

WALTER A. DORSEY, OF COLUMBUS, OHIO, ASSIGNOR TO THE BONNEY FLOYD COMPANY,
OF COLUMBUS, OHIO, A CORPORATION OF OHIO.

CAR-MOVING TOOL.

1,311,803.

Specification of Letters Patent. Patented July 29, 1919.

Application filed December 3, 1917. Serial No. 205,190.

To all whom it may concern:

Be it known that I, WALTER A. DORSEY, a citizen of the United States, residing at Columbus, in the county of Franklin and State of Ohio, have invented certain new and useful Improvements in Car-Moving Tools, of which the following is a specification, reference being had therein to the accompanying drawing.

This invention relates to improvements in tools for manually moving cars on tracks, the tools being adapted to apply leverage to the peripheries of the wheels while being fulcrumed on the track rail.

Each of these tools, as commonly made, is provided with a fulcrum device comprising one or two small pieces of metal, each piece being hardened and having one or more edges which are relatively sharpened so that it can, under weight and pressure, obtain a firm surface bite upon the top of a rail and be capable of withstanding the great tendency at the edge to become dulled, marred and broken.

The length of time during which one of these tools is really available is governed by the period during which the hardened fulcrum pieces are available for their work. In some cases these fulcrum elements have been each formed of two similar pieces of steel, each piece being an elongated quadrangular prism; that is to say, it has four elongated rectangular side faces and square ends and is square in cross section. The tools are used at points distant from shops and sometimes must be used constantly for long periods. And as the implements have been heretofore made, they become useless at an early moment because the fulcrum pieces, even though they are capable of being adjusted to two or three new positions before they are worn out, rapidly become marred or dulled so as to slip upon the rail.

One of the objects of my invention is to provide a tool of this class with a system of fulcrum pieces by which its period of use can be greatly extended.

In the drawings—

Figure 1 is a side view of a car-moving tool embodying my improvements;

Fig. 2 is a side view showing the positions

assumed by the parts of the tool after the car wheel has begun to be moved;

Fig. 3 is a view partly in side elevation and partly in section of the handle socket 55 part of the device.

Fig. 4 is a top view of the socket.

Fig. 5 is a side view of the pinch bar element, one of the arms 9 being broken away to show the inner face of the other arm.

Fig. 6 is a top view of the same.

Fig. 7 is a vertical cross section, showing a part of a rail and also the pinch bar, taken on the plane of the fulera.

Fig. 8 is a perspective of one of the fulcrum blocks detached.

The tool, as an entirety, comprises three main parts, A, B and C. Those at A and B together constitute the main lever, and C, the pinch bar. The part B is formed of metal and is cast with a socket part 1, a central hinge section 2, and a forwardly projecting short arm or operative element 3 having a wide top flange 4, an end flange 5, and a web 6, together with stop lugs at 7.

The handle A is firmly inserted in the socket part 1 of the element B.

The pinch bar element C is a lever formed with the wheel-engaging forward portion 8 and the two parallel arms 9 extending backward therefrom, these being spaced as shown at 10 (Fig. 6) to permit the forward arm 3 of the element B to lie between them and move vertically relatively thereto. The front part 8 is formed with a toe 11 for direct engagement with the periphery of the wheel and also with two strong downwardly extending spurs or lugs 12 which guide the tool along the top of the rail when it is pushed forward or drawn backward. The elements B and C are hinged together by the cross pivot 13 which passes through the rear ends of the arms 9 and through the central part 2 of the element B.

On each side of the toe portion 8 there is formed a socket which extends horizontally inward, the two sockets being separated by a wall 15 integral with the toe. Each socket has two walls 16 and 17 which are equal in width, and two walls 18 and 19 at right angles to each other but narrower

than the walls 16, 17, the planes of those at 18 and 19 intersecting the plane of the bottom surface 20 of the said forward portion 8 of the pinch bar. Consequently, there are two slots 21 through this bottom surface, one at the lower edge of each socket 14. E, E, indicate the fulcrum devices. They are formed of hardened steel and each is as nearly an exact cube as it can be practically made. The cross section of each of the sockets 14 is the same as the cross section of one of the cubes except for slight clearance to permit the cubes to be inserted or withdrawn; and in depth, horizontally, the socket is of a dimension twice as great, so that two of the cubes can be snugly inserted into each socket. The cross dimension of the toe part 8 is sufficiently greater than the cross dimension of the rail, as shown in Fig. 7, to always have at least one of the cubes on the right and one on the left engaging with the rail surface, the preferred working position of the tool being indicated in that figure.

25 The cubes are held in place by washers 22 fitted against the side faces of the toe 8 and a bolt 23 with its head on one side and a nut 24 on the other.

I have found that when properly constructed the edge of a single cube, when arranged as shown, can carry the load in serving as a fulcrum. If, when two edges are at work, one of them should become crushed or dulled, the other one will continue for an average normal period of work. And by having the fulcrum pieces in the shape of perfect cubes the fulcrum devices, as an entirety, provide for continuing in operation at points distant from the shop during a period which is forty-eight times as long as the period of life of any one edge. The cube can be so positioned in relation to the socket that it can be adjusted around not one axis but three axes. And there are four possible adjustments for operation around each of the axes; or a total of twelve all together. In other words, a cube fulcrum block can be taken out by releasing the bolt and washers and can be turned to have either 50 of twelve operative edges brought into use.

The sockets for these cubes are on transverse lines close to those of the side guides or lugs 12 so that the tool can be turned around the fulcrum axis as far as necessary 55 without disengaging the lugs from the rails.

The solid central flange or wall 15 between the sockets 14 and integral with the metal behind the sockets and with the forward part 8 overcomes the liability heretofore met with of having the rear parts of the metal behind the sockets so weak as to readily break when powerful strains are exerted.

The mode of operating the tool, and the 65 course to be followed in adjusting its parts,

will be readily understood by those acquainted with such matters. When a car is to be moved, the tool is thrust into the angle between the periphery of the car wheel D and the rail F and brought to the position 70 shown in Fig. 1. The operator then bears downward upon the handle part A and the parts are so proportioned that both the main lever element A, B, and the pinch lever C engage with the wheel periphery and swing 75 upward therewith at their front ends, the movement of the entire tool occurring around the bite line of the cube blocks E as an axis, and the supplemental movement of the main lever A, B, occurring around the 80 axis of the hinge at 13. If, after a period of use, it is observed that either one of the fulcrum cubes has become marred or broken at its bite edge, the washers are loosened and this cube is withdrawn from the socket. If 85 there are still operative edges parallel to the one that has been marred, the cube is turned around the axis parallel to said edge until a new edge is in position to project through the slot 21, and then the blocks are clamped 90 again in position. If, on withdrawal of a cube, it is found that no one of its edges parallel to the last one marred or worn is capable of further use, the cube is turned around to bring one of its other axes in 95 alignment with the socket and is adjusted to have a fresh new operative edge project through the slot, and the parts are again clamped rigidly in position.

What I claim is:

1. In a car-moving tool, the combination with the main lever, of the pinch bar hinged thereto and having the solid forward end part 8 formed with a transverse socket which is approximately square in cross section and 100 with a slot through the lower surface communicating with the said socket, and a series of hardened cubical fulcrum blocks each adapted to be inserted along either of three axes into the said socket and to be fitted 105 tightly therein in either of four positions relatively to each of said axes, and means for locking the said fulcrum cubes in the socket substantially as set forth.

2. In a car-moving tool, the combination 115 with the main lever, of the pinch bar hinged thereto and having the solid forward end part 8 formed with two horizontally opposite transverse sockets and an integral vertical wall between them, each socket being 120 approximately square in cross section and the part 8 having a slot in its lower surface communicating with each socket, and two series of hardened cubical fulcrum blocks, those of each series being positioned in one 125 of the said sockets and each being adapted to be fitted in a socket to expose through the slot either of twelve equal operative edges substantially as set forth.

3. In a car moving lever, the combination 130

of means for engaging a car wheel, a pinch bar pivotally connected with said engaging means for applying pressure on the wheel and on the track, a removable and adjustable fulcrum element seated in a socket in the pinch bar and having one of its edges projecting below the face of the pinch bar, and means for holding the fulcrum element in its socket, said fulcrum element being cubical

and adapted, by adjustment as described, to 10 present any of the twelve edges for engagement with the track.

In testimony thereof, I affix my signature, in presence of two witnesses.

WALTER A. DORSEY.
